United States Patent Office.

WILLIAM A. LEWIS AND GEORGE W. BUTLER, OF JOLIET, ILLINOIS.

Letters Patent No. 96,818, dated November 16, 1869.

IMPROVEMENT IN MACHINE FOR CUTTING FELLOES.

The Schedule referred to in these Letters Patent and making part of the same.

Be it known that we, WILLIAM A. LEWIS and GEORGE W. BUTLER, of Joliet, in Will county, and State of Illinois, have invented a new and improved Machine for Cutting out Wagon-Felloes; and we do hereby declare the following to be a full, clear, and exact description of the same, reference being had to the annexed drawings, making a part of this specification, in which—

Figure 1 is a perspective view;
Figure 2, a plane view on the top;
Figure 3, a rear elevation;
Figure 4, a perspective view of a single cutting-bit; and

Figure 5, a view on the bottom of said bit to show the curve of its outer side.

This machine may be constructed wholly or in part of metal, as desired, and is operated and arranged as we shall now proceed to explain, relying as much on the representations in the drawings as in the description, to convey our ideas.

t is a frame, upon which rests an adjustable table in two separate parts, *b* and *c*, supported by the main frame *a*.

These parts may be moved to or from each other by means of the counter screw *j*, figs 2 and 3, which is boxed in the counter frame *a*, at each end, and is attached to the two parts of the table *b* and *c*, by means of the nut-boxes *n* and *o*, fig. 3.

It will be readily observed that by turning said screw, each part of the table will be moved either to or from the other, according to the direction the screw is turned, which is for the purpose of adjusting the dogs *e* and *l* to any distance apart, to accommodate the machine to any length of the piece to be cut.

The set-screws *s* and slots prevent the tables from being moved too far either way.

The adjustable table rests upon the frame *t*, which may be moved horizontally, by means of the screw *d*, operating in the nut *p*, attached to said frame, as shown in fig. 2.

This is for the purpose of accommodating the dogs *e* and *l* to any circle to which the cutting-bits *v* may be set to cut.

The dog *e* is arranged to slide laterally, by means of the lever *i*, to receive the block to be cut between them, as it rests upon the rests 8 and 9, shown in fig. 1.

f is an adjustable gauge, to regulate the distance the block is to be shoved into the machine between the dogs, so that the cut may be uniform each time.

This gauge *f* is operated by the levers *g* and *h*, attached to the dog *e*, as shown in fig. 2, and is regulated by means of the slide *q* and set-screw *r*.

z is an upright shaft, standing in a step, 4, on the elliptical spring 1, upon which it is allowed to move perpendicularly, by means of the levers 2 and 3, the lever 2 having a forked end, which engages with said

shaft, as shown in fig. 3, to bring it down, which is done by pressing down with the foot on the end of the lever 3, fig. 1.

The cutter-head *m* is attached to said shaft, as shown in figs. 1 and 3, and revolves by means of a belt on the pulley 5.

A double row of concentric cutting-bits *v* are attached to said cutter-head, and are arranged in radial slots, as shown in figs. 1 and 2, by means of which they may be set to cut any desired circle, and may also be set at any distance apart, to cut any width of a felloe.

The cutting-bits are constructed in about the shape shown in figs. 4 and 5.

Fig. 4 is a perspective view of a single bit, which is constructed with a projection on the upper part, which fits into a corresponding groove on the under side of the cutter-head, shown at 6, figs. 1 and 3, the object of which is to prevent the bit from turning around while at work.

A cross-section of the cutting-bit is shown at 7, fig. 5, curved at the outer side, so as to inscribe a circle, to clear the walls of the cut it makes.

We are aware that machines have been before used, in looks quite similar, for the same purpose, but being objectionable, as compared with this, in several respects, the main ones of which are that a separate machine has had to be used for every different circle desired to be cut, while in this machine any circle practicable may be cut, simply by adjusting the cutting-bits to suit the circle.

Also, the cutting-bits are brought down to their work, instead of the work being brought up to the bits, which is a great improvement, as can be readily seen, as the table is left perfectly solid and stationary, a desirable feature when we contemplate that the variation of one-sixteenth of an inch will spoil the work for felloes, which is invariably the case when the table is moved up and down.

Claims.

We claim—

1. The combination and arrangement of the shaft *z*, cutter-head *m*, cutting-bits *v*, levers 2 and 3, step 4, elliptical spring 1, table *b* and *c*, dogs *e* and *l*, levers *i*, *g*, and *h*, gauge *f*, and main frame *a*, constructed and operating as and for the purposes set forth.

2. The combination and arrangement of the dogs *e* and *l*, levers, *i*, *g*, and *h*, gauge *f*, slide *q*, set-screw *r*, and adjustable table *b* and *c*, as and for the purposes set forth.

W. A. LEWIS.
GEORGE W. BUTLER.
